US00D942129S

(12) **United States Design Patent** (10) Patent No.: **US D942,129 S**
(45) Date of Patent: **** Feb. 1, 2022**

(54) **SHOE**

(71) Applicant: **SMART ONLINE SHOPPING TECHNOLOGY GLOBAL LTD,**
Singapore (SG)

(72) Inventor: **Jie Huang**, Singapore (SG)

(73) Assignee: **SMART ONLINE SHOPPING TECHNOLOGY GLOBAL LTD,**
Singapore (SG)

(**) Term: **15 Years**

(21) Appl. No.: **29/758,559**

(22) Filed: **Nov. 17, 2020**

(51) LOC (13) Cl. **02-04**

(52) U.S. Cl.

USPC **D2/923**; D2/939

Primary Examiner — Jonathan J Han

(57) **CLAIM**

The ornamental design for a shoe, as shown and described.

DESCRIPTION

FIG. 1 is a perspective view of a shoe showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the shoe that form no part of the claimed design.

1 Claim, 8 Drawing Sheets
